UNITED STATES PATENT OFFICE.

SAMUEL E. COGSWELL, OF PRETTY PRAIRIE, KANSAS.

POULTRY-FOUNTAIN.

SPECIFICATION forming part of Letters Patent No. 723,651, dated March 24, 1903.

Application filed November 18, 1902. Serial No. 131,868. (No model.)

To all whom it may concern:

Be it known that I, SAMUEL E. COGSWELL, a citizen of the United States, residing at Pretty Prairie, in the county of Reno and State of Kansas, have invented certain new and useful Improvements in Poultry-Fountains, of which the following is a specification, reference being had therein to the accompanying drawings.

10 This invention relates to improvements in devices for supplying water to poultry.

The object is to provide an automatically-acting fountain which will retain a relatively large body of water and deliver it to an open vessel at intervals, according as it is withdrawn by the fowls. Devices of numerous sorts have been heretofore proposed for this purpose; but the object of the present invention is to provide a method of manufacture 20 and a resulting article which shall have incident to them a minimum of cost and at the same time be available for attaining all of the purposes that are aimed at when employing these devices.

25 Figure 1 is a vertical section of a watering device embodying my improvements. Fig. 2 is a bottom end view of the main water-receptacle. Fig. 3 is a perspective showing the receptacle in the position occupied by it after 30 it has been filled and at the time it is being inverted and placed in the water-delivering vessel.

In the drawings, A indicates the body part 35 of the water-holding vessel. In order to insure the least possible cost in the construction of the article, I so arrange and relate the parts that use can be made of the cheapest kinds of tin vessels. The central portion of such a vessel or can is shown at a, it having 40 the permanently-fastened cover a' and the bottom a². An aperture is formed at a³ in this bottom, and in the aperture there is placed a delivery-tube B, which is secured to the bottom wall by solder.

45 C C are legs or supports for the can or vessel, they consisting of pieces of wire or light rods of a length somewhat greater than the delivery-tube B. They are secured in place by solder or equivalent fastening at c.

50 F indicates the water-delivering vessel, which is placed below the main holder A. In manufacturing these devices I prefer to fur-

nish as part of each implement a tin saucer-like or shallow dish, such as indicated in the drawings; but it will be seen that the main 55 water-retaining vessel A is of such character that the user can employ dishes or pans of any of many styles and accomplish all the desired purposes. The principal requisite is that the delivering vessel F should be of a depth somewhat greater than the distance from the bottom f to the lower end of the delivering-tube B.

The manner of using the device I have described will be readily understood. When it 65 is desired to water the fowls, the vessel A is inverted and filled with water through the tube B. A body of water should also be put into the delivering vessel F. Then by placing the finger in the way shown at F', so as to 70 close the lower end of the tube B, the can or vessel A can be turned over and put into the position in the pan F shown in Fig. 1. Thereafter the water will be delivered from the upper vessel A to the lower one in the well-known way—that is to say, when sufficient 75 water has been withdrawn from the pan F to bring the level of the remainder to the plane of the lower end of the tube B or slightly below it air will enter through the tube B into 80 the vessel A and displace part of the water therefrom, which will continue until the surface of the water in the pan F again rises above the lower end of the tube B. When it reaches said end, the tube will be sealed 85 against the entrance of any more air.

As above stated, I am aware of the fact that other devices of this class have been made or proposed; but I believe myself to be the first to have devised a simple and economical fountain of the sort set forth.

90 By having the canister or vessel A, its delivery-tube, and its supporting-legs entirely detachable from the pan F the latter can be readily and completely cleaned at any time, 95 the device in this respect being superior to those in which the pan or water-delivering part has been provided with arms or projections, which would interfere with the rapid cleaning.

100 What I claim is—

The herein-described automatically-acting poultry-watering device having a pan F of relatively large diameter and a canister A of

shorter diameter, having air-tight sides and top a' and provided with legs C, shorter than the depth of the pan, and with a reduced tubular escape-tube B, the pan F supporting the canister and being entirely detachable therefrom, said parts being constructed and arranged substantially as set forth.

In testimony whereof I affix my signature in presence of two witnesses.

SAMUEL E. COGSWELL.
